PANEL FOR LIGHTING FIXTURE OR THE LIKE

Leo G. Stahlhut, Kirkwood, and Carl X. Meyer, St. Louis
County, Mo., assignors to Day-Brite Lighting, Inc., St.
Louis, Mo., a corporation of Missouri

Application June 7, 1956, Serial No. 41,805

Term of patent 14 years

(Cl. D48—16)

FIG. 1

FIG. 2

FIG. 3

FIG. 4

FIG.5

Fig. 1 is a perspective view of a panel for lighting fixture embodying our new design, the panel being viewed from below,

Fig. 2 is a plan view of the panel,

Fig. 3 is a greatly enlarged fragmentary transverse sectional view taken substantially along line 3—3 of Fig. 2,

Fig. 4 is a greatly enlarged fragmentary perspective view similar to Fig. 1, and

Fig. 5 is a greatly enlarged fragmentary perspective view similar to Fig. 4 but showing the reverse side.

We claim:

The ornamental design for a panel for lighting fixture or the like, substantially as shown.
